UNITED STATES PATENT OFFICE.

EDWARD E. WHITMORE, OF CHICAGO, ILLINOIS, ASSIGNOR TO THE CURTAIN SUPPLY COMPANY, OF NEWARK, NEW JERSEY, A CORPORATION OF NEW JERSEY.

CURTAIN-FIXTURE.

1,036,045.

Specification of Letters Patent. Patented Aug. 20, 1912.

Application filed August 5, 1909. Serial No. 511,264.

To all whom it may concern:

Be it known that I, EDWARD E. WHITMORE, a citizen of the United States, residing at Chicago, in the county of Cook and State of Illinois, have invented certain new and useful Improvements in Curtain-Fixtures, of which the following is a specification.

The present invention relates to curtain fixtures of the class or kind in which the curtains are mounted on spring-actuated rollers tending at all times to wind or roll up such curtains, the latter being held down in proper position by suitable holding means carried by the curtain stick provided at the bottom of the curtain. In the present instance I aim to supply at each side of the curtain an anti-friction outwardly spring-pressed head which is intended and adapted to travel at all times freely and easily in the guiding grooves of the window casing or side posts. In conjunction with such easily movable heads I employ friction or holding means to co-act with the bottoms of such guiding grooves, whereby to hold the curtains down in operative adjusted position. These friction members are connected at the center of the curtain stick with finger knobs or clasps which are adapted to retract them, whereby to render them temporarily inoperative as holding means, and when thus held back the curtain is free to move to the desired position, the antifriction shoes or heads at all times remaining in the grooves, and because of their elongated character tending to hold the curtain stick in proper righted horizontal position.

In the accompanying drawing, which forms a part of this specification, I have shown a desirable embodiment of this invention, and in this drawing—Figure 1 is a fragmentary front view of a window casing equipped with a curtain having one of my improved curtain fixtures, certain parts being broken away to more clearly illustrate the internal construction; Fig. 2 is an enlarged vertical section through the window casing and a portion of the curtain fixture; Fig. 3 is a similar view of a modified construction; Fig. 4 is an edge view of the fixture shown in Fig. 3; and Fig. 5 is a view similar to Fig. 3 of a still further modified construction.

In this particular embodiment of the invention the curtain 10 is mounted on a

spring-actuated roller 11 which exerts a constant tendency to wind or roll up the curtain thereon, and at its lower end the curtain has extended therethrough a tubular stick 12 having inserted in its central portion a short inner tube 13, the latter in turn having fixed in its center a stationary block 14. At each end of such tubular stick I provide a hollow sheet-metal head 13^a of substantial length transversely of such stick, the head being suitably fixed to a cylindrical barrel or stem 14^a fitted and slidable in the end of such stick. The elongated head, as stated above, is made of sheet-metal and is composed of two side members 15 connected at their backs by a portion 16 which in the present instance is apertured for the reception of the outer end of the barrel or stem 14^a, the part protruding through such hole into the interior of the head being riveted to the latter at 17 and 18. At each end the head 13^a carries a revoluble anti-friction roller 19 mounted thereon for rotation in any suitable and convenient manner. The heads and rollers are adapted to fit and travel in the grooves 20 formed on the inner faces of the side posts 21 of the window casing, the heads being partially received within such grooves, as is clearly indicated. In order to press outwardly these heads and associated rollers each end of the hollow stick is supplied with a coil expansion spring 20^a, the outer end of which bears against the corresponding barrel or stem 14^a, while its inner end bears against a perforated washer 21^a held against inward movement in the stick by indentations 22 in the latter. It will, therefore, be obvious and apparent that, owing to the expansive character of such springs, the normal tendency is for these anti-friction heads to be held in such position that all of the rollers 19 contact and engage with the bottoms of the guiding grooves 20.

To supply means for holding the curtain in adjusted position, I provide the following instrumentalities: Each head has pivoted therein between its two sides 15 on a fulcrum pin 23 a cam 24, the outer face of which is adapted to be pressed into frictional engagement with the bottom of the groove 20 to constitute a frictional holding means to maintain the curtain in the desired position. In normal condition, as is indicated in Fig. 2, a portion of the cam protrudes out of the head 13 so as to bear against the

bottom of the groove. At its upper bifurcated end this cam is slotted at 25 for the accommodation of a connecting pin 26 which protrudes into such slot and through 5 the reduced end of a rod 27 passing axially through a central opening 28 in the barrel or stem 14^a and also through the central hole of the washer 21. Approximately midway of its length such rod is equipped 10 with a washer 29 fitted and prevented from outward movement thereon by the enlargement 30 of the rod, such washer, through the central hole of which the rod passes, acting as an abutment against which the 15 outer end of the coil expansion spring 31 may press, the inner end of such spring bearing against the adjacent end of the inner tube 13. To the inner end of each rod 27 I fasten the shank 32 of a finger piece 33, 20 the main body of which is disposed outside of the stick and curtain, having a portion projecting through a slot into the interior thereof.

The operation of this appliance is substantially as follows: Under normal conditions the antifriction heads 13 with their rollers 19 are pressed into the guiding grooves 20 by the pair of expansion springs 20^a, the rollers bearing against the bottoms 30 of the grooves, as will be readily understood. The springs 31 in turn force outwardly the rods 27, the latter through their slot and pin connections with the cams rocking them upon their pivot or fulcrum pins 23 so as to secure a firm and effective frictional engagement between the cams and the bottoms of the grooves to prevent movement of the curtain in either direction. In order 35 to adjust the height of the curtain to that 40 which may be desired, the operator ordinarily grasps the two finger pieces 33, pressing the same together, thereby drawing inwardly the pair of rods 27 against the action of the two springs 31, and rocking the 45 two cams 24 away from the bottoms of the grooves into the dotted line position shown in Fig. 2. This action on the part of the operator withdraws the holding friction and permits the curtain to be raised and lowered, the anti-friction elongated heads readily and easily traveling in the guiding grooves and acting, because of their elongated character, to maintain the curtain stick in righted condition. It should be observed that when the curtain is released in 55 this manner the operation and retraction of the cams in no way influences the cooperative relation between the anti-friction heads and the guiding grooves, and it should be 60 further noticed that even if the stick is considerably tilted or inclined, due to improper manipulation owing to the yielding character of the springs 20^a the heads will remain partly in the grooves and prevent dis- 65 placement or dislodgment of the curtain

stick. After the curtain has been brought to the desired height the operator releases the pincers or finger pieces 33, and the cams under the action of the springs may rock on their pivots so as to again operatively and frictionally engage the bottoms of the grooves to hold the curtain in adjusted position. 70

If it be attempted to raise the curtain by pushing up the stick without pinching the handles together the cams will sometimes hold so firmly to the bottoms of the grooves that they will be rotated on their pivot pins 23 until the pins 26 occupy the upper ends of the slots 25, the heads being forced back 80 slightly by the pressure exerted thereupon by the cams through the pins 23. Further turning movement of the cams being now impossible, the cams will slide along the bottoms of the grooves and the curtain will 85 be permitted to move upward without injury to the holding device. If upward pressure be applied to the stick by the hand of the operator near one end, the lower end of the head at the other end of the stick will 90 be only slightly withdrawn from the groove before the device will right itself, for the reason that the cam of this head can extend out beyond its normal position but slightly, owing to the fact that the pin 26 reaches 95 the end of the slot 25 before the cam has turned on its pivot to any considerable extent. The practical advantage of this self-righting feature in a device of this kind is 100 well understood to those skilled in this art. 100

The modified construction of Fig. 3 is substantially like that of Fig. 2, except that the head 34 is made integral with its barrel or shank 35 and the aperture 36 extended through the latter is somewhat larger than the corresponding aperture in the construction of Figs. 1 and 2 to permit a slight lateral movement of the rod 27, which in this instance is directly pivoted at 37 to the top end of a curved cam 38 pivoted to the head 39. Inasmuch as the operation of this cam is substantially like that of the one described above, further description of the same appears to be unnecessary, it being sufficient to state that because of the lack of the provision of the pin and slot connection the rod 27 moves sidewise to an extent and that the larger hole 36 is provided for this reason. In this style of device it is evident that the amount of "throw" of the cam 38 is determined by the degree of lateral play permitted by the rod 27 in the stem 36. 115

Instead of making the pin and slot connection between the rod 27 and the cam, the former may be directly pivoted as at 40 120 (Fig. 5) to the top end of a cam which is connected to the anti-friction head 13 by means of a pin 41 rigid with the latter and passing through a slot 42 of the cam. Obviously, then, as the rod 27 is shifted the cam 125 130

not only rocks on its pivot pin 41 but also slides somewhat over the same, as I have indicated in dotted lines in Fig. 5. The action of this cam, however, is practically the same as the others described, the amount of "throw" being determined by the length of the slot 42.

These are only a few of a considerable number of embodiments of which this invention is susceptible, and I do not, therefore, wish to be limited to any of these exact constructions, since many minor mechanical changes in the same will occur to those skilled in this art, and the incorporation of such changes in structures of this character would not constitute a departure from the heart and essence of this invention.

I claim:

1. In a curtain fixture, the combination of a curtain stick, anti-friction heads mounted on said stick and adapted to travel in the guiding grooves of a window or other casing, spring means to press said anti-friction heads outwardly into said grooves, independent spring-pressed friction cams pivoted on said heads and adapted to hold the curtain from movement by pressure against the bottoms of said grooves, retracting means for said cams to render the same temporarily inoperative, thereby permitting adjustment of said curtain and the free travel of said heads in said grooves, and means for limiting the movement of said cams relatively to its head, substantially as described.

2. In a curtain fixture, the combination of a curtain stick, a head mounted in the end of said stick and movable therein, anti-friction rollers on said head, spring means for pressing said head outwardly into a groove in the casing, a cam pivoted to said head, a rod within said curtain stick and having slotted engagement with said cam, spring means for pressing said cam outwardly into said groove, thereby preventing vertical movement of said curtain stick, and means for retracting said rod and thereby withdrawing said cam from its engagement with

the bottom of said groove, thereby allowing vertical movement of said curtain stick, substantially as described.

3. In a curtain fixture, the combination of a stick, a head having anti-friction means above and below the stick, spring means for pressing the head outwardly, a cam pivoted in said head, spring means for moving said cam outwardly, means in said head for limiting the movement of said cam, and manually operable means for retracting said cam.

4. In a curtain fixture, the combination of a stick, a spring pressed head carried by the stick, anti-friction means carried by the head above and below the plane of the stick, a cam pivoted in said head, a rod connected to said cam and extending into the stick, a spring for urging said rod outwardly, means for limiting the movement of said rod with respect to the head, and means for retracting said rod to withdraw said cam from holding engagement with the window frame.

5. In a curtain fixture, the combination of a stick, a spring pressed head having anti-friction means above and below the stick, a holding cam mounted in said head, spring means for revolving said cam outward, and means for limiting the movement of said cam with respect to said head.

6. In a curtain fixture, the combination of a curtain stick, a spring pressed head carried by the stick, anti-friction means carried by the head and located above and below the plane of the stick, a rod confined to longitudinal movement within the stick, a spring pressing said rod outwardly, a cam pivoted to the end of the stick and to the head, said cam having a slotted connection with one of its pivots, and means for retracting said rod to withdraw said cam from holding engagement with the window frame, substantially as described.
